UNITED STATES PATENT OFFICE.

RICHARD K. WALTON, OF CLARINGTON, OHIO.

IMPROVEMENT IN MINERS' PICKS.

Specification forming part of Letters Patent No. **144,808**, dated November 18, 1873; application filed July 21, 1873.

To all whom it may concern:

Be it known that I, RICHARD K. WALTON, of Clarington, in the county of Monroe and State of Ohio, have invented a new and Improved Miner's Pick; and I do hereby declare the following to be a full, clear, and exact description of the same, reference being had to the accompanying drawing forming part of this specification, in which—

Figure 1 is a side elevation, partly broken out. Fig. 2 is a front view of bit, and Fig. 3 is an end view of bit.

My invention is a movable bit to be attached to an ordinary pick-head, and prevented from turning by a clamp-screw. This bit is provided with two triangular-shaped points.

A is the movable bit, the back of which is either slightly curved or straight, according to the manner in which it is to be used. The sides of the bit are usually made parallel. Upon the lower side of the bit is cut an angular-shaped groove, b, which makes at the end of the bit two triangular-shaped points, a a. B is a shank provided with a thread, which

screws into the head C, being held from turning by the clamp-screw D, which terminates on a flattened side of the pin B.

The pick-head is similar in shape to that of an ordinary miner's pick.

To use the pick, it may be attached to a common pick-handle, or to a machine made for this purpose.

Having thus described my invention, what I claim as new, and desire to secure by Letters Patent, is—

1. As an improvement in miners' picks, the detachable bit A, having the angular groove b and the triangular-shaped points a a, as shown and described.

2. The bit A, provided with a screw-threaded tenon having a flattened side, in combination with a head, C, and clamp-screw D, as shown and described, for the purpose specified.

RICHARD K. WALTON.
